F. ARMBROSTER

WINDOW OR DOOR STOP

Filed Apr. 13, 1921

Inventor
F. Armbruster
By his Attorney
Maxwell C. Spamer

UNITED STATES PATENT OFFICE.

FREDERICK ARMBROSTER, OF AVERNE, NEW YORK.

WINDOW OR DOOR STOP.

Application filed April 13, 1921. Serial No. 460,939.

To all whom it may concern:

Be it known that I, FREDERICK ARMBROSTER, a citizen of the United States, and resident of 63-14 Boulevard, Averne, in the 5 county of Queens and State of New York, have invented certain new and useful Improvements in Window or Door Stops, of which the following is a specification.

This invention relates to improvements in 10 window or door stops.

An object of this invention is to provide an economical, efficient and effective window or door stop, simple in construction, and adapted to be used for preventing a window 15 or door from being stealthily opened or to keep a door in any desirable open position or preventing same from closing when in open position.

Another object of this invention is to provide 20 a stop of the character stated above and wherein a metallic wedge-shaped bearing member is sunk within a deeply grooved non-metallic wedge-shaped body, said bearing member being provided with a tapered 25 knife-edge pin protruding outwardly from the bottom of said body nearest that portion of the stop having the greatest height, the latter pin being adapted to be sunk into the wooden frame of a window or a floor.

30 The above and further objects in view will more fully be understood from the following description together with the accompanying drawings forming part of this specification and in which:—

35 Figure 1 illustrates how the device may be applied as a window stop.

Figure 2 illustrates how the device may be applied as a door stop.

Figure 3 illustrates a longitudinal sec- 40 tional view of the device.

Figure 4 illustrates a bottom view of the same.

Figure 5 illustrates a modified form of the device.

45 In the drawings there is disclosed a wedge-shaped wooden body 11 having a flat bottom or base 12, said body being of the same width throughout.

The upper or bearing surface 13 of body 50 11 has a maximum height at the point indicated by the numeral 14 from which point bearing surface 13 declines relative to base 12 until it meets the latter so as to form a dull edge 15.

55 End 16 of body 11 is made perpendicular

to base 12, the corner joining said end with bearing surface 13 being rounded off as indicated by the numeral 17.

Within body 11 there is formed a narrow, deep groove indicated by the dotted 60 lines at 18. (See Figure 4.)

This groove has its walls formed perpendicular to base 11 and equidistant from the inclined sides 19 of body 11 and is located equidistant from the latter's end 16 and 65 edge 15. The bottom of the groove is made parallel with base 12.

Tightly fitting into this groove is a wedge-shaped bearing member 20 conforming to the shape of the groove. The inclined surface of bearing member 20 is flush with the bearing surface 13 of body 11. This bearing member is provided with a tapered knife-edge projection or pin 21, made integral therewith, and protruding 70 outwardly from base 12 of body 11 nearest that portion of the stop having the greatest height.

Projection 21 is so disposed without body 11, that its knife-edge is parallel with and 75 equidistant from, the inclined sides 19 of said body. Its shape and disposition is such that when it is caused to be sunk within a wooden frame or floor it leaves but a small perforation.

80 Body 11 may be provided with a vertical perforation to accommodate pin 21 or the pin may be forced through the body when bearing member 20 is caused to fit into its groove, by suitable means.

85 Bearing member 20 with its knife-edge projection 21 is made preferably from steel or any other suitable hardened metal. The purpose of this bearing member is to provide a hardened contact surface adapted to 90 resist pressure applied to the stop at its inclined surface the shape of this member being such that the greater the applied pressure the greater the tenacity or unyieldingness of knife-edge pin or projection 21 when 95 in contact with the window frame or floor.

95 Figure 5 shows the stop in a modified form. Instead of knife-edge projection 21 being made integral with bearing member 20, it is made a separate element in the form 100 of a pin 22.

105 When the stop is constructed according to this modified form it is preferable to have pin 22 shaped so as to form tapered edges at both ends, the inner end engaging the 110

body 11, the outer end adapted to engage the floor or window in the manner described below.

The stop described above is adapted to be used for preventing a window or a door from being stealthily opened. Figure 1 shows how the stop is applied to prevent windows from being opened. The stop is secured to the frame of the upper window with its 10 tapered edge facing down, the knife-edge projection or pin 21 being sunk within said frame. On account of the shape and disposition of said projection 21, but a small perforation is made within the frame, which 15 perforation will always mark the place at which the stop is to be replaced when desired.

If an attempt is made to raise the bottom or lower the top window the stop will intercede and prevent said opening. Of course one of the windows will open slightly at the bottom or top depending upon whether the attempt is made to lower the top window or raise the bottom one, on account of the 25 amount of play between the windows. For this reason it is not necessary to have the surface of bearing member 20 come down to the extreme lower end of the stop.

Figure 2 shows how the stop is applied to prevent a door from being opened. Similarly to that stated above, the door will open slightly and if an attempt is made to force the door beyond that point, the latter will bear against the inclined surface of the 35 stop thereby exerting a substantially vertical pressure upon bearing member 20 which in turn strengthens the unyieldingness of its projection 21.

Having thus described my invention and reserving for myself the right to make alterations and amendments within the purview of my idea, I claim.

1. A window or door stop comprising in combination a wedge-shaped body, a wedge-shaped bearing member tightly fitted within said body, said bearing member being provided with a knife-edge pin made integral therewith and protruding outwardly from the bottom of said body, substantially as described.

2. A window or door stop comprising in combination a wedge-shaped body, a wedge-shaped bearing member provided with a

knife-edge pin protruding outwardly from the bottom of said body, said wedge-shaped body having formed therein a groove to conform with the shape of said bearing member, substantially as described.

3. As a new article of manufacture a window or door stop comprising in combination a wedge-shaped body having inclined sides and provided with a groove, a wedge-shaped bearing member provided with a knife-edge pin, adapted to fit into said groove, said pin being protruded outwardly at a right angle to the base of said body in such manner that its knife-edge is parallel with and equidistant from the inclined sides of said body, substantially as described.

4. As a new article of manufacture a window or door lock comprising in combination a wedge-shaped body having inclined sides and provided with a groove, said groove having its walls formed perpendicular to the base of said body and equidistant from the inclined sides of the latter, a wedge-shaped bearing member provided with a knife-edge pin, adapted to fit into said groove, said pin being protruded outwardly at a right angle to the base of said body in such manner that its knife-edge is parallel with and equidistant from the inclined sides of said body, substantially as described.

5. A window or door stop comprising in combination a wedge-shaped body having inclined sides and an end perpendicular to its base, said body being provided with a groove disposed equidistant from its ends and having its greatest depth near the greatest height of said body, said groove having its walls formed perpendicular to the base of said body and equidistant from the inclined sides of the latter, a wedge-shaped bearing member provided with a knife-edge pin, adapted to fit flush into said groove, said pin being protruded outwardly at a right angle to the base of said body in such manner that its knife-edge is parallel with and equidistant from the inclined sides of said body, substantially as described.

Signed at New York, in the county of New York and State of New York this 26 day of March, A. D. 1921.

FREDERICK ARMBROSTER.
